R. D. HUGHES

MEASURING CAN

Filed April 18, 1927

UNITED STATES PATENT OFFICE.

ROBERT D. HUGHES, OF DAYTON, OHIO, ASSIGNOR TO THE HUFFMAN MANUFACTURING COMPANY, OF DAYTON, OHIO, A CORPORATION OF OHIO.

MEASURING CAN.

Application filed April 18, 1927. Serial No. 184,502.

This invention relates to measuring cans and more particularly to that type of can in which the oil or other liquid is discharged from the bottom through a flexible spout 5 which delivers it to the crank case of an automobile engine or to some other more or less accessible point of delivery.

Measuring cans of this type are extensively employed at automobile filling stations where the measuring can is filled at an oil tank within the station and then carried to the automobile outside the station. When the can is filled full there is a tendency of the oil to splash over the edge, or to 15 spill if the can is slightly tilted.

One object of the present invention is to provide a measuring can of this type with a guard which will effectually prevent the spilling of the oil without in any way interfering with the free visibility of the measuring line at the top of the can, to which line the can must be filled.

A further object of the invention is to provide a simple efficient operating mechanism for the valve which controls the discharge of the liquid from the can; and to provide such a mechanism which will require the use of but a single supporting member within the can.

30 Other objects of the invention will appear as the device is described in detail.

In the accompanying drawings Fig. 1 is a top plan view of a measuring can embodying my invention; Fig. 2 is a vertical sectional view of the same; Fig. 3 is a sectional view of the thumb piece, taken on the line 3-3 of Fig. 2; Fig. 4 is a sectional view of the guard, taken on the line 4-4 of Fig. 2; Fig. 5 is a plan view of the guide for the 40 valve stem, taken on the line 5-5 of Fig. 2; Fig. 6 is a detail view of the guide for the actuating rod; and Fig. 7 is a detail view of a portion of the actuating rod.

In these drawings I have illustrated one embodiment of my invention but it will be understood that this particular embodiment has been chosen for the purpose of illustration only and that the device may take various forms without departing from the spirit 50 of the invention.

As here shown, the measuring can comprises a body portion 1, the walls of which converge upwardly so that the body portion forms in effect the frustum of a cone. A 55 bottom plate 2 is mounted within the body

portion of the can and is spaced some distance above the lower edge of the body portion, that part of the body portion beneath the bottom constituting a support for the can. The bottom 2 of the can has near its 60 forward edge an outlet opening with which is connected a discharge spout 3, and the bottom is depressed so that the liquid will drain from all parts thereof toward the discharge spout. The discharge spout extends 65 downwardly and forwardly from the outlet in the bottom of the can and projects through an opening in the lower portion or skirt of the body of the can. This spout is of a flexible character so that its outer or discharge 70 end may be moved either into an elevated position, as shown in Fig. 2, or into a position below the level of the bottom 2 of the can so that the liquid will discharge through the same. This flexibility may be secured in 75 various ways but, in the present instance, I have formed the spout in part of flexible tubing, as shown at 4. A hook shaped catch 5 secured to the upper portion of the can serves to retain the spout normally in its 80 elevated position.

The discharge opening leading to the spout 3 is controlled by a valve 6 which seats upon the upper surface of the bottom 2 about the opening. Secured to the valve 85 6 is a valve stem 7 which extends upwardly from the valve through a guide 8 secured to the wall of the can, and a spring 9 confined between the valve and the guide holds the valve normally on its seat. Mounted in the 90 can above the bottom thereof is a supporting structure or bracket 10 on which is pivotally mounted a lever 11, one end of which is pivotally connected with the valve stem 7 and the other end of which is pivotally connected 95 with the lower end of an actuating rod 12 which extends to a point above the top of the can and is there provided with a thumb piece 13 so arranged that it may be engaged by the thumb of the hand which grasps the 100 handle 14, by means of which the can is carried. The supporting structure or bracket 10 and the guide 8 for the valve stem are preferably of such a character that they may be mounted as a unit on the side of the can. 105

As here shown, the bracket comprises an outer portion which fits against the forward wall of the can at a point some distance above the outlet, to which it is rigidly secured by soldering or otherwise. Formed 110

integral with this outer portion of the bracket are two inwardly extending arms 15 which preferably converge inwardly and between the inner ends of which the lever 11 is mounted. In the present instance, the lever is secured in position between the two arms of the bracket by a pivot pin 16, here shown as a cotter pin, which also serves to connect the inner ends of the arms. The 10 guide 8 for the valve stem is mounted in fixed relation to the arms 15 and is preferably an integral part of the bracket. This guide is here shown as comprising an inwardly extending lip or plate arranged in a substantially horizontal position and having an opening 17 to receive the valve stem 7. The lateral edges of the guide plate 8 lie adjacent to or extend slightly beyond the corresponding arms 15, and the opening 17 in 15 the guide plate is here shown as a slot opening through one edge thereof and consequently when the valve stem is in position within this slot the adjacent arm 15 will retain the same therein. In assembling the 20 valve and its operating mechanism the bracket 10, comprising the arms 15 and the guide plate 8, is rigidly secured to the wall of the can in the desired position with relation to the outlet. The valve, valve stem 25 and lever 11, are assembled as a unit before being introduced into the can, and that arm 15 of the bracket which is adjacent to the open end of the slot 17 is bent outwardly so that the valve may be placed in position, the 30 spring 9 compressed and the valve stem inserted in the slot, after which the arm 15 is returned to its normal position and the pivot pin is inserted through the two arms and the lever to connect the arms together and to 35 pivotally support the lever. The connecting rod 12 is usually connected with the lever after the latter has been mounted in the can, this being done to enable the rod to be inserted through a guide 18 extending in 40 wardly from the upper portion of the can. This guide preferably has a slot extending forwardly from the guide opening, as shown at 19, and the rod 12 has its sides recessed, as shown at 20, these recessed portions being 45 so arranged that when the rod has been depressed to open the valve the recessed portion of the rod will slip forwardly into the slot 19 and thus lock the valve in its open position.

50 The thumb piece 13 at the upper end of the rod may take various forms but, in the present instance, it comprises a rod or bar, preferably an integral part of the rod 12, bent into substantially rectangular shape, as 55 shown at 21, this rectangular portion extending rearwardly from the rod and being preferably arranged at a slight inclination to facilitate its engagement by the thumb. A plate or cover strip 22, of metal or other 60 suitable material, is then mounted on the

side members of the rectangular portion of the thumb piece, this plate being here shown as secured to the side members of the part 21 by bending the edges of the plate about the respective side members, as shown in Fig. 3. 70

The upper edge of the body portion 1 of the can constitutes a measuring line, as shown at 1^a, that is, the line to which the measure is filled. In the present device, the guide 18 also acts as a measuring line to indicate when the measure is full and to this end the guide 18 is so mounted on the body portion of the can that the lower surface thereof will be in the same plane with the upper edge of the body portion. This guide 75 extending inwardly from the wall provides a very easily seen indication of the level of the liquid. Secured to the upper edge of the body portion 1 is a guard or rim 23 which extends entirely about the can and is so shaped that it will prevent the oil from splashing or spilling over the upper edge of the can. Preferably this consists of a single annular rim of metal which is curved 80 outwardly and upwardly, as shown in Figs. 2 and 4, and the upper portion of which is turned inwardly as shown at 24. The portion 24 extends inwardly only a short distance so that the diameter of the opening at the top of the guard is materially greater 85 than the diameter of the upper end of the can, and the reading line 1^a, formed by the upper edge of the body portion, is at all times unobscured and easily seen by the operator. Thus the can can be filled and the location of the liquid with relation to the measuring line easily determined, and when the can is full it may be carried without danger of spilling the oil. 90

While I have shown and described one 105 embodiment of my invention I wish it to be understood that I do not desire to be limited to the details thereof as various modifications may occur to a person skilled in the art.

Having now fully described my invention, what I claim as new and desire to secure by Letters Patent, is:

1. In a measuring can, a body portion having an open upper end and having an outlet near its lower end, and a guard rim extending outwardly about the entire circumference of the upper edge of said body portion and having its outer portion turned upwardly and inwardly. 115

2. In a measuring can, an upright body portion having an outlet near its lower end and having its upper end open, the upper edge of said body portion constituting a measuring line, and an annular guard rim secured to the upper end of said body portion, extending outwardly and upwardly therefrom and having its upper end extending inwardly, the diameter of the opening at the top of said guard rim being materially 120

greater than the diameter of the upper end of said body portion.

3. In a measuring can, a body portion having a bottom provided with an outlet, a discharge spout communicating with said outlet, a valve to control the flow of liquid through said outlet, a stem for said valve, a bracket secured to the wall of said body portion at one side thereof and above said bottom, and 10 having a part forming a guide for said valve stem, a lever pivotally mounted on said bracket and connected with said valve stem, and an actuating member connected with said lever and having a part arranged 15 above said body portion.

4. In a measuring can, a body portion having a bottom provided with an outlet, a discharge spout communicating with said outlet, a valve to control the flow of liquid 20 through said outlet, a stem for said valve, a bracket secured to the wall of said body portion above said outlet and having an inwardly extending portion, a lever pivotally supported by the inwardly extending portion 25 of said bracket, a guide for said valve stem carried by said bracket and arranged adjacent to the lower edge of said inwardly extending portion of said bracket, and an actuating member connected with said lever 30 and having a part arranged above said body portion.

5. In a measuring can, a body portion having a bottom provided with an outlet, a discharge spout communicating with said outlet, a valve to control the flow of liquid 35 through said outlet, a stem for said valve, a bracket rigidly secured to the wall of said body portion above said opening and comprising rearwardly converging portions and 40 a horizontal portion arranged beneath said rearwardly converging portions and having

a slot opening through one edge thereof to receive said valve stem, means for connecting the rear ends of said converging portions of said bracket, one to the other and 45 for pivotally supporting a lever between the same, means for operatively connecting one end of said lever with said valve stem above said guide, and an actuating rod pivotally connected with the other end of said lever 50 and extending above the top of said body portion.

6. In a measuring can, a body portion having an outlet near its lower end and having its upper end open, a valve to control 55 said outlet, a valve actuating device mounted within said body portion and connected with said lever, said valve actuating device comprising a rod extending beyond the upper end of said body portion, and a guide for 60 said rod comprising an apertured plate secured to the upper part of said body portion and having an opening to receive said rod, said plate being so arranged with relation to said body portion that one surface 65 thereof constitutes a measuring line to indicate the quantity of liquid in said can.

7. In a measuring can, a body portion having an outlet near its lower end and having its upper end open, a valve to control 70 said outlet, a valve actuating device mounted within said body portion and connected with said valve, said valve actuating device comprising a rod extending beyond the upper end of said body portion and having 75 its upper end bent laterally and then upon itself to form a laterally extending loop, and a plate extending between and secured to the side members of said loop.

In testimony whereof, I affix my signature 80 hereto.

ROBERT D. HUGHES.
